UNITED STATES PATENT OFFICE.

WILLIAM HENRY SWAN, OF KANKAKEE, ILLINOIS.

CHURN-DASHER.

SPECIFICATION forming part of Letters Patent No. 634,377, dated October 3, 1899.

Application filed May 12, 1899. Serial No. 716,574. (No model.)

To all whom it may concern:

Be it known that I, WILLIAM HENRY SWAN, of Kankakee, in the county of Kankakee and State of Illinois, have invented a new and Improved Churn-Dasher, of which the following is a full, clear, and exact description.

The object of my invention is to provide a churn-handle with a set of rotary dashers so constructed that in churning the dashers will 10 rotate in opposite directions and the motion of the dashers be reversed automatically by the up-and-down movement of the handle.

Another object of the invention is to provide a simple and economic churn-dasher that 15 will not splash the cream, thus enabling the churn to be filled nearly to the top.

A further object is to provide a construction of dashers that may be kept perfectly clean and the lower dasher be mounted to 20 rotate at the bottom of the churn.

Another object of the invention is to so construct the dashers that they may be quickly and conveniently placed upon the handle or removed therefrom.

25 The invention consists in the novel construction and combination of the several parts, as will be hereinafter fully set forth, and pointed out in the claims.

Reference is to be had to the accompanying 30 drawings, forming a part of this specification, in which similar characters of reference indicate corresponding parts in all the figures.

Figure 1 is a side elevation of a portion of the handle and two dashers mounted thereon. 35 Fig. 2 is a horizontal section through the handle, taken on the line 2-2 of Fig. 1, showing the lower dasher and spacing-block in plan view; and Fig. 3 is a side elevation of the lower portion of the handle, the dashers having been removed.

The handle A is reduced in diameter at the bottom, forming a lower shoulder 10 and an upper shoulder 11, and centrally between these two shoulders the handle is recessed at 40 both sides, forming a flat section 12 between an upper cylindrical section 13 and a lower cylindrical section 14. The dashers employed are usually two in number, B and C, although a single dasher may be used, if desired. Each 45 dasher is made in two sections, the sections of the lower dasher B being designated as b and b' and the sections of the upper dasher

C as c and c'. Each section of the lower dasher B consists of a square hub 15 and blades 16, that extend from opposite sides of 55 the hub. These blades are inclined in opposite directions, and the opposing faces of the hubs of the sections b and b' are provided with recesses 17, as shown in Fig. 1, whereby the hubs of the two sections are interlocked, 60 one section being at right angles to the other. A recess 18 is made in the bottom surface of the hub of the lower dasher B, which recess (shown in Fig. 1) is adapted to receive that portion of the handle below the shoulder 10, 65 and the lower hub is therefore adapted to rest upon the said shoulder, since the hubs are provided with a central opening of greater diameter than the diameter of the cylindrical section 14 of the handle. Thus it will be observed that the bottom of the lower dasher will be at the bottom of the handle, and the dasher may be brought close to the bottom of 70 the churn.

The sections of the upper dasher C are interlocked in like manner as the sections of the lower dasher B, and each section consists of a hub 19, having a central opening of greater diameter than the cylindrical surface 13 of the handle, and blades 20, extending from opposite sides, the said blades of each section being oppositely inclined, and the blades of the upper dasher C are at an angle to the blades of the lower dasher B. The hubs of each dasher are provided with a diagonal slot 85 21, extending from a point between the blades and connecting with the central opening of the hubs, as shown in both Figs. 1 and 2. A recess 21^a is made in the upper surface of the upper hub of the upper dasher C, and this 90 recess is adapted to receive that portion of the handle A that is just above the upper shoulder 11.

The dashers are placed upon the handle by entering the flat section 12 of the handle into 95 the slots 21 and carrying the dashers toward the handle until one dasher can be carried up on the cylindrical surface 13 of the handle and the other down upon the cylindrical surface 14. The dashers are free to rotate and 100 are held apart by a spacing-block 22, which is made in two sections connected by a wire 23. The wire normally connects these sections at one end of the spacing-block only and

extends beyond the opposite end of the block, and the spacing-block is provided with a central opening of sufficient size and shape to neatly receive the flat section 12 of the handle.

- 5 When the sections of the spacing-block have been opened and the spacing-block is placed on the handle at the flat section 12, the extending ends 24 of the handle-wire 23 are twisted together, thus holding the block in place; but other forms of fastening device 10 may be substituted, if desired.

It will be observed that when churn-dashers are constructed as above set forth said dashers will turn in opposite directions and 15 reverse automatically with the up-and-down motion of the handle that carries them.

Having thus described my invention, I claim as new and desire to secure by Letters Patent—

- 20 1. A churn-dasher comprising a handle having a journal formed thereon for the reception of the blades, and a flattened section adjacent the journal and contained within the circle thereof in combination with a dasher having 25 a central hole adapted to fit on the journal and a slot extending from said hole to the exterior and adapted to pass the flattened section of the handle, substantially as described.

2. A churn-dasher, comprising a handle 30 having a journal formed thereon for the reception of the blades, and a flattened section adjacent the journal and contained within the circle thereof in combination with a dasher formed of crossed bars recessed to interlock, and provided with angularly-disposed 35 blades forming a wheel, said wheel having a central hole adapted to receive the journal

and a slot extending from this hole to the exterior and adapted to pass the flattened section of the handle, substantially as described. 40

3. A churn-dasher, comprising a handle having two journals of reduced diameter formed thereon for the reception of the wheels or blades, a flattened section between the journals and contained within the circle thereof, in combination with wheels or dashers each having a central hole adapted to fit on its journal, a slot extending from said hole to the exterior and adapted to pass the flattened section of the handle, and a removable spacing 45 washer or block between the two dashers, substantially as described.

4. A churn-dasher, comprising a handle having two journals of reduced diameter formed thereon for the reception of the wheels or blades, and a flattened section between the two journals and contained within the circle thereof, in combination with wheels or dashers each formed of crossed bars recessed to interlock and provided with angularly-disposed 60 blades forming a wheel, said wheel having a central hole adapted to receive its journal and a slot extending from the hole to the exterior and adapted to pass the flattened section of the handle and a two-part spacing- 65 washer adapted to be secured by the flattened section of the handle between the two wheels after the wheels are in place, substantially as described.
